UNITED STATES PATENT OFFICE

126,183

DESIGN FOR A COASTER

Francis J. Curran, Oak Park, Ill.

Application November 22, 1940, Serial No. 96,732

Term of patent 14 years

To all whom it may concern:

Be it known that I, Francis J. Curran, a citizen of the United States, residing at Oak Park, in the county of Cook and State of Illinois, have invented a new, original, and ornamental Design for a Coaster, of which the following is a specification, reference being had to the accompanying drawing, forming a part thereof.

In the drawing:

Fig. 1 is a top plan view of a coaster, showing my new design; and

Fig. 2 is a side elevational view thereof.

Fig. 3 is an enlarged fragmentary sectional view, taken on the line 3—3 of Fig. 1 and in the direction of the arrows.

I claim:

The ornamental design for a coaster, as shown.
FRANCIS J. CURRAN.
